UNITED STATES PATENT OFFICE.

JAMES A. WOTTON, OF MONTCLAIR, NEW JERSEY, ASSIGNOR TO WESTERN ELECTRIC COMPANY, INCORPORATED, OF NEW YORK, N. Y., A CORPORATION OF NEW YORK.

DESIGN FOR A TELEPHONE-RECEIVER SUPPORT.

53,000.

Specification for Design.

Patented Feb. 11, 1919.

Application filed November 3, 1917. Serial No. 200,204. Term of patent 14 years.

To all whom it may concern:

Be it known that I, JAMES A. WOTTON, a citizen of the United States, residing at Montclair, in the county of Essex and State of New Jersey, have invented a new, original, and ornamental Design for Telephone-Receiver Supports, of which the following is a specification, reference being had to the accompanying drawing, forming part thereof.

In the drawing, Figure 1 is a side elevation and Fig. 2 is a plan view of a telephone support showing my new design.

I claim:—

The ornamental design for a telephone receiver support, as shown.

In witness whereof, I hereunto subscribe my name this 30th day of October 1917.

JAMES A. WOTTON.
